FLOOR SCRAPER

Herman Siemund, Chicago, Ill., assignor to
Greenview Manufacturing Company, Chicago,
Ill., a corporation of Illinois

Application May 20, 1937, Serial No. 143,827

2 Claims. (Cl. 15—245)

The present invention relates generally to scrapers, squeegees and the like, and it has particular relation to an improved curved type scraper or squeegee, which is specially designed and adapted for cleaning low flat surfaces, such as floors and the like, with a push or pull stroke while permitting the operator to remain in an erect or standing position.

One object of the invention is to provide a curved floor scraper or squeegee having a plurality of flexible wiping blades.

Another object of the invention is to provide a curved floor scraper or squeegee having a flexible wiping blade along all edges or faces thereof.

15 A further object of the invention is to provide a curved floor scraper or squeegee having one or more wiping faces or edges with a reversible handle mechanism, which permits the operator to manipulate the scraper on either horizontal wiping face with a pull or push stroke—toward or away movement—while standing in substantially an erect position.

Another object of the invention is to provide a curved floor scraper or squeegee having a plurality of angular wiping surfaces, viz: horizontal and/or vertical planes, making it especially adapted for cleaning low floor surfaces adjacent corners and highly polished or painted sidewall moldings without scratching or otherwise mar-

30 ring the latter.

Other and further objects and advantages of the invention reside in the detailed construction of the scraper or squeegee, which result in simplicity, economy and efficiency, and which will be apparent from the following description, wherein a preferred form of embodiment of the invention is shown, reference being had to the accompanying drawing, forming a part hereof, in which:

40 Fig. 1 is a perspective view of a curved floor scraper or squeegee constructed in accordance with my invention;

Fig. 2 is a fragmentary top plan view, on an enlarged scale, of the scraper or squeegee shown 45 in Fig. 1;

Fig. 3 is a cross-sectional view of the scraper or squeegee shown in Fig. 2, the same being taken along the line 3—3 thereof, looking in the direction of the arrows; with the reverse position of 50 the handle mechanism being shown in dotted lines;

Fig. 4 is a cross-sectional view of the scraper or squeegee shown in Fig. 3, with the opposite horizontal wiping edge being shown in the floor en-

5 gaging position and illustrating the position of the respective movable parts of the reversible handle mechanism; and also showing the reverse position of the handle mechanism in dotted lines;

Fig. 5 is a fragmentary perspective view of the outer arcuate frame member of my improved 5 scraper;

Fig. 6 is a fragmentary perspective view of the flexible wiping blade member; and

Fig. 7 is a fragmentary perspective view of the inner arcuate frame member. 10

Referring now in detail to the drawing, there is shown in Fig. 1 a curved floor scraper or squeegee 10, having a relatively narrow outer arcuate frame member 11, provided with a series of longitudinally spaced apertures 13 extending therethrough; a relatively wide flat flexible wiping blade member 15, made of rubber or other suitable material, provided with a series of apertures 17 spaced longitudinally thereof in corresponding position to the apertures 13 of the outer arcuate frame member 11; and an inner relatively narrow arcuate frame member 19, provided with a series of relatively short circumferentially extending slots 21 spaced longitudinally thereof in corresponding position to the apertures 13 and 17 of 20 the members 11 and 15 respectively. The inner frame 19 and the outer frame 11 are made of relatively light, durable, stainless and/or non-corrosive metal. 15

The flexible wiping blade 15 is adapted to be 30 removably secured or clamped between the outer arcuate frame member 11 and the inner arcuate frame member 19, and when arranged in proper relationship the apertures 13 and 17 and the slots 21 are in perfect radial alignment for receiving 35 bolts 23, which are inserted through the front frame member 11 and securely fastened in the aligned openings by means of nuts 25 threaded to the projecting ends thereof beyond the inner frame 19. It will be noted that the relatively 40 wide flexible wiping blade 15 now projects outwardly on all sides of the arcuate metal frame members 11 and 19, thereby providing a flexible wiping edge on all sides thereof and in different horizontal and vertical parallel planes. The 45 purpose of the circumferential slots 21 in the arcuate frame member 19 is to facilitate assembling of the scraper or squeegee, and to compensate for any slight variation in the arcuate shape 50 of the metal frames 11 and 19 in the event they are not of identical shape.

Mounted centrally of the back side of the inner arcuate frame member 19 is a relatively large U-shaped bracket 27, having radially inwardly extending arms 29, provided with aligned open- 55

ings 31 adjacent the ends thereof for reception of a bolt or rod 32, which is mounted transversely of the arms 29 to provide an axle or shaft, the same being held in position by means of a nut 33 threaded to the end thereof. A second relatively small U-shaped bracket 35, having short inwardly extending arms 37 provided with aligned openings adjacent the ends thereof is pivotally mounted in reverse position on the shaft 32 between the arms 29 of the U-shaped bracket 27.

A handle receiving hollow socket member 37 is provided with a transversely extending L-shaped front attaching bar 39, having its long arm 41 secured to the outwardly projecting back of the small U-shaped bracket member 35 by means of bolts 43 and nuts 45, and its short arm 47 extending inwardly between the arms 37 of the bracket 35 toward the scraper 10. A relatively long wooden handle 49, as best shown in Fig. 1, may be inserted in the hollow socket member 37 to permit ready manipulation of the scraper or squeegee from an erect or standing position.

As best shown in Fig. 3, the scraper 10, with its concave side adjacent the operator, is shown with its wiping edge 51 maintained in floor engaging or operating position. The full line position of the handle 37 illustrates its respective position when the scraper 10 is being pulled toward the operator, and the dotted line position of the handle 37 illustrates its respective position when the scraper 10 is being pushed away from the operator.

In Fig. 4 of the drawing, the scraper 10 is shown with its opposite horizontal wiping edge 53 maintained in floor engaging or operating position, the concave side thereof still being next to the operator. In this figure the full line position of the handle member 37 illustrates its respective position when the scraper 10 is being pulled toward the operator, and the dotted line position of the handle member 37 illustrates its respective position when the scraper 10 is being pushed away from the operator.

The handle mechanism 37 is suitably braced, or reinforced, as best shown in Figs. 1 and 2, by a pair of diverging and laterally extending brace rods 55 positioned symmetrically of the arms 29 of the bracket 27. The brace rods 55 are of angular shape, having their outer ends 57 bent arcuately to conform to the curvature of the inner frame member 19 to which they are to be secured, and the inner ends 59 are bent backwardly at an oblique angle to the curved outer ends thereof to be secured to the shaft 32 mounted adjacent the ends of the arms 29 of the U-shaped bracket 27. The curved outer ends 57 of the brace rods 55 are secured at spaced intervals to the inner arcuate frame member 19 adjacent the outer ends thereof by means of the bolts 23 and nuts 25.

Thus, it will be readily seen that the scraper 10 may be operated with either a pull or push movement, and with either its concave side toward the operator or away from the operator, as desired by merely flipping or reversing the handle 49. By providing the scraper 10 with flexible wiping edges on all faces thereof, the operator not only has a plurality of separate wiping edges, but also has a plurality of angular wiping surfaces for simultaneously cleaning corners adjacent the floor and the molding, either on the

right or left side without necessitating reversing of the handle 49 or turning over the scraper 10. Obviously, with a plurality of individual wiping surfaces, the flexible wiping member will give much longer service than if only one side thereof could be utilized for, if one side becomes badly worn, the opposite side may be used exclusively until it becomes worn out. Then, too, the provision of a plurality of wiping surfaces in different planes, together with the reversibility of the handle member 49, enables an operator to change positions easily and quickly when the present position becomes tiresome from constant movement of a single form of stroke, thereby enabling the operator to clean a much larger space with less tiring effort than that heretofore enjoyed by the single edge type of floor scraper device.

Although I have only described one form of the invention, it will be readily apparent to those skilled in the art that the invention is not so limited, but that various modifications may be made therein without departing from the spirit thereof or from the scope of the appended claims.

What I claim is:

1. In a reversible squeegee of the class described, a pair of arcuate frame members, a wiping element adapted to be secured therebetween having a plurality of wiping edges extending beyond all sides of said frame members, means for removably securing said wiping element between said frame members, a frame structure mounted centrally of the back of said inner frame member having a pair of spaced arms projecting rearwardly on opposite sides of the center of said inner frame member, a shaft mounted between the ends of said spaced arms, a second frame structure having forwardly extending arms adapted to be pivotally secured to said shaft, a handle receiving member mounted on the back of said second frame structure for receiving a removable handle, and a pair of brace rods extending obliquely from the opposite ends of said shaft to a point intermediate the sides of said inner frame member.

2. In a reversible squeegee of the class described, a pair of arcuate frame members, a wiping element adapted to be secured therebetween having a plurality of wiping edges extending beyond all sides of said frame members, means for removably securing said wiping element between said frame members, a frame structure mounted centrally of the back of said inner frame member having a pair of spaced arms projecting rearwardly on opposite sides of the center of said inner frame member, a shaft mounted between the ends of said spaced arms, a second frame structure having forwardly extending arms adapted to be pivotally secured to said shaft, a handle receiving member mounted on the back of said second frame structure for receiving a removable handle, and a pair of brace rods extending obliquely from the opposite ends of said shaft to a point intermediate the sides of said inner frame member, said brace rods being curved adjacent their extreme outer ends to conform to the arcuate shape of the ends of said inner frame member, said curved ends of said brace rods being secured at spaced intervals to said inner frame member.

HERMAN SIEMUND. 70
